OIL BURNER MANIPULATING MECHANISM

Edmund E. Allyne, Cleveland, Ohio

Application August 13, 1931, Serial No. 556,745

1 Claim. (Cl. 126—44)

The invention disclosed herein relates to oil burning apparatus.

When oil burners of the burner and vertically movable shell type are used in connection with 5 refrigerating apparatus, for example, where the still is to be heated by the burner, all of this mechanism including the still is usually arranged in a so-called apparatus compartment open at the front and arranged in the bottom of the 10 refrigerating cabinet. Since it is necessary to have access to the burner for lighting, filling and other purposes and to have the burner properly located under the still, for example, it is important that the burner mechanism as a whole be 15 arranged so that it is accessible at the front opening of the apparatus compartment and is provided with means for raising and lowering the shell without direct contact with it.

It is the object of this invention to meet the 20 foregoing requirements and in so doing the entire burner structure as a unit is pivotally mounted just inside of the front opening of the apparatus compartment with the pivot substantially under the fuel reservoir so that the burner part 25 may be swung laterally through an arc of substantially 90° to either expose it at said opening or to bring it into proper heating relation with the bottom of the still, a suitable handle forming a part of the burner apparatus being provided for 30 this purpose. In addition to the pivoting of the entire burner so as to swing in the manner just stated, the burner structure is provided with a shell manipulating device in the form of a loop or bail pivoted on a standard forming a part of 35 the burner unit and having engaging loops or recesses passing under suitable trunnions arranged on the side of the shell. The burner end of the loop or bail is extended out beyond the shell to form a handle for raising the shell for light- 40 ing purposes. The opposite end of the loop or bail extends oppositely from the pivot around and beyond the reservoir and above the turning handle so that the operator may also depress this end of the loop and so raise the shell.

45 The invention is well set forth in the following description, drawing and claim.

Referring to the drawing, Fig. 1 is a front elevation of a portion of the apparatus compartment with the burner mechanism shown in elevation and in the front or lighting position; Fig. 2 is a 50 top plan view; and Fig. 3 is a fragmental detail view showing the bracket with the pivot.

In the embodiment shown, 1 represents the main casing of the refrigerating cabinet, which usually is provided with an angle frame including

the front and side angles 2. To the front angle is secured a flange 3 of a bracket 4 which extends horizontally into the compartment near the bottom of the angle. This bracket is provided with an upstanding pivot 5. The framework of the cabinet is also usually provided with a cross strut 6 extending from the side angles and from this cross strut under a still 7, for example, is a diagonally extending guide or rod 8 secured to the front angle to form a support and guide for engaging under the burner end of the burner unit. Any suitable type of oil burner unit may be arranged in this way but the one shown is of popular type and consists of a reservoir generally indicated at 9, a fuel pipe 10 extending outwardly from the bottom thereof and supporting the oil burner 11. Slidably mounted upon this burner is the usual burner casing or shell generally indicated at 12 and which must be raised for igniting and other purposes.

Extending upwardly from the fuel pipe 10 between the reservoir and burner is an upright or standard 13 provided with lateral pins 14. Engaging these pins are bearing portions 15 formed on the sides of a bail or loop-shaped lever frame 16 20 preferably of wire. The two end loops of this frame surround the shell of the burner on the one end and the reservoir on the other. The sides of the loop surrounding the burner shell are bent to form sockets 17 adapted to engage pins or trunnions 18 projecting outwardly from the sides of the burner shell. The burner end of the loop is continued beyond the shell to form a handle as indicated at 19 and the opposite loop about the reservoir is extended beyond the 25 reservoir to form a handle as at 20. Either of the handles 19 or 20 may be used for the purpose of elevating the shell for lighting or other purposes.

The burner structure thus far described is 40 also provided with a frame comprising at the reservoir end a bracket 21 having a handle 22 at the top and a lower plate portion 23 extending under the burner structure and secured to the fuel pipe 10. This plate is provided with a suitable opening or socket 24 for receiving the pin 5 carried by the bracket 4. The other end of the plate 23 is adapted to slide upon the guide 8.

From the foregoing it will be observed that the burner unit comprises burner and reservoir members fastened to the same frame and mounted to swing horizontally about the center of the reservoir, as an axis. The reservoir is always accessible just within or at the opening in the casing and by rotating the unit frame in the manner 55

described the burner can be moved about the pivot 5 to either of two positions, to wit, the full line position, Fig. 2, just inside of and accessible through the opening in the front of the apparatus casing so that the burner is thus accessible for igniting or other purposes, or to a second position, shown in dotted lines Fig. 2, in which the burner is beneath the device to be heated, such as the still 7. In both positions the reservoir is equally accessible. The burner unit frame is mounted upon a bracket attached to the frame of the casing near its front and extending rearwardly toward the still position, and slides upon the supporting bar 8. Said unit frame also serves as the support for the side standards 13 on which the pivoted lever 16 is mounted, and whatever be the position of the parts, either the full line position or the dotted line position, and whether the operator is working with the reser-

voir or with the burner, a part of said lever is convenient for manipulation to raise the burner shell. Moreover, the entire burner unit may be readily lifted off and taken out of the casing for any purpose, whenever desired. 5

Having described my invention, I claim:

Apparatus of the character described, comprising a hollow casing having a frame and provided with an opening, a burner unit supported on said frame within said opening, said unit including vertically extending reservoir and burner members located side by side, a unit frame supporting the same, standards extending upwardly from said unit frame, and a two-armed lever supported on said standards and comprising arms 15 embracing and extending endwise beyond the reservoir and burner members and connected to the latter for operation thereof from either end of the unit frame. 10
